UNITED STATES PATENT OFFICE.

JOHN J. ROHRBAUGH, OF HOPEWELL, VIRGINIA.

FLAG-HALYARD.

1,360,584.

Specification of Letters Patent. Patented Nov. 30, 1920.

Application filed August 5, 1920. Serial No. 401,477.

To all whom it may concern:

Be it known that I, JOHN J. ROHRBAUGH, a citizen of the United States of America, residing at Hopewell, in the county of Prince George and State of Virginia, have invented certain new and useful Improvements in Flag-Halyards, of which the following is a description.

The present method of raising and displaying flags results in a very great financial loss to the Government and individuals inasmuch as the flag is rigidly connected to the halyard at its top and bottom edge which results in the flag whipping in the wind thereby tearing and fraying the outer free end of the flag; besides which the flag frequently tears at its lower inner corner where it is rigidly connected to the halyard. Again in the present method of displaying flags one end of the halyard frequently becomes loose thereby making it necessary for some one to climb the flag pole to recover the flag and when it is understood that the regular charge for such recovery of the flag at National cemeteries is ten dollars (\$10.00) it will be appreciated that some means to eliminate such accidents is highly desirable.

The object of my invention is to provide an endless halyard for flags and to provide means on the halyard to which the flag may be attached so that the flag may be free to spill the wind thereby eliminating the whipping, fraying and tearing of the flag.

A further object of my invention is to provide an endless halyard with two flag attaching means, one of said means being rigidly secured to the halyard while the other of said means is freely and slidably mounted on said halyard and also free to move relatively and transversely of the halyard; and with these and other objects in view my invention consists of the parts and combination of parts as will be hereinafter pointed out.

Figure 1 is an elevation of a flag mast with halyard attached thereto, embodying my invention, and flag attached to the halyard.

Fig. 2, is an enlarged detail sectional view showing one of my improved fasteners attached to the halyard.

Fig. 3, is a top plan view of Fig. 2, the parts being in full line.

Fig. 4, is a perspective view of lower fas-

tener, in connection with which is shown a portion of the halyard.

The reference numeral 1 designates a flag mast of any desired type having a pulley 2 suitably secured at the top of 60 the pole.

The halyard 3 is an endless one mounted in the pulley 2. In providing an endless halyard I eliminate all possibility of the halyard becoming loose and the incident 65 cost of the same as herein explained.

A flag attaching means 4, which may be a casting, is provided at its rear portion with a tubular part 5 through which the halyard may be threaded and in which the 70 halyard is secured against relative movement by means of the set screws 6. The attaching means 4 is provided at its front portion with a snap hook construction 7 which is adapted to engage the ring 8 in 75 the upper corner of the flag.

The halyard is provided with a second flag attaching means which consists of an elongated body member 9 to one end of which an enlarged ring 10 is integrally secured, and to the other end of which a snap hook 11 is integrally secured. The ring 10 is of a diameter which is materially greater than the diameter of the halyard with which it is intended to be used so that it may be 80 free to loosely slide up and down on the halyard and also free to move transversely relatively to the halyard.

When a flag is connected to its halyard according to my invention there is no possibility of its being frayed, whipped or torn because when the wind strikes it, the ring 10 of the fastener 9 is free to and will slide up and down on the halyard and thereby permit the flag to spill the wind and at 95 the same time retain sufficient wind pressure to maintain it in extended position. Ordinary wind pressure will be taken care of by the relative transverse movement of the ring 10 while greater pressure will be 100 taken care of by this transverse movement of the ring 10 plus the flexibility of the halyard.

This invention has been in actual practical use for some time at one of the National 105 cemeteries in this country and its use has resulted cutting down the number of flags used per year exactly one-half which has resulted in a material saving to the Government besides which there has been no 110

expense for recovering flags due to lost hal-yards.

The bodily outward movement of the flag and upward movement of its lower edge materially increases the beauty of the undulations of the flag while flying.

What I claim is:

A flag halyard comprising an endless flexible cable adapted to be mounted in a pulley 10 on a flag pole, a tubular block through which the halyard is passed and to which the block is rigidly but detachably secured, a fastener carried by said block to which one corner of a flag may be secured, a sec-

ond flag fastener mounted on the halyard 15 and free to move on the halyard and adapted to be secured to a corner of the flag whereby the second fastener is free to move up and down on the halyard as wind strikes the flag, whereby the flag is free at its inner 20 end to bulge outwardly and move upwardly at its lower edge to spill the wind, thereby eliminating the whipping and tearing of the flag.

In testimony whereof I affix my signature.

JOHN J. ROHRBAUGH.
